(57) **CLAIM**

The ornamental design for an extrusion tool, as shown and described.

DESCRIPTION

FIG. 1 is a front top isometric view of an extrusion tool of my new design;

FIG. 2 is a front elevation view of the extrusion tool of my new design, the rear, left, and right elevation views being identical thereto; and,

FIG. 3 is a top plan view of the extrusion tool of my new design.

The broken lines in the drawings depict portions of the extrusion tool which form no part of the claimed design.
